UNITED STATES PATENT OFFICE.

ABRAHAM E. PERREN, OF BUFFALO, NEW YORK.

DESIGN FOR A RUNNING-GEAR FOR SLEIGHS.

SPECIFICATION forming part of Design No. 24,315, dated May 14, 1895.

Application filed December 31, 1894. Serial No. 533,476. Term of patent 7 years.

To all whom it may concern:

Be it known that I, ABRAHAM E. PERREN, a citizen of the United States, residing at the city of Buffalo, in the county of Erie and State 5 of New York, have invented and produced a new and original Design for Running-Gear for Sleighs, of which the following is a specification.

This design relates to the configuration of 10 the running-gear of sleighs, and is represented in the accompanying drawing, which forms a part of this specification, and which is a perspective view of a running-gear embodying my design.

15 The leading feature of my design consists of the convex form of the front knees in connection with the ogee or upwardly contracted form of the rear knees.

20 A A represent the runners; B, the front cross piece or bench; C, the front knees; D, the rear cross piece or bench, and E the rear knees.

25 As shown in the drawing a pair of front knees C extends from each end of the front bench downwardly to the runner. The knees of each pair diverge downwardly fore and aft of the running gear and their upper portions

are curved and arranged with their convex sides outwardly, so that the front knees on each side of the running gear have an outwardly bulging or convex appearance. 30

A pair of rear knees E extends from each end of the rear bench downwardly to the runner. The knees of each pair diverge downwardly fore and aft, like the front knees but 35 the rear knees are made of ogee or upwardly contracted form, the upper portion of each knee being concave on its outer side and the lower portion convex.

The combined effect of the convex front 40 knees and the ogee or upwardly contracted rear knees is that of a broad running gear from the front and a narrow running gear from the rear.

What I claim is—

45 The design for the running gear of a sleigh, substantially as herein shown and described.

Witness my hand this 28th day of December, 1894.

ABRAHAM E. PERREN.
